UNITED STATES PATENT OFFICE.

CHARLES W. LUMMIS, OF WORCESTER, MASSACHUSETTS, ASSIGNOR TO MORGAN CONSTRUCTION COMPANY, A CORPORATION OF MASSACHUSETTS.

FEEDING MECHANISM FOR GAS-PRODUCERS.

1,274,176.

Specification of Letters Patent. Patented July 30, 1918.

Application filed June 28, 1915. Serial No. 36,626.

To all whom it may concern:

Be it known that I, CHARLES W. LUMMIS, a citizen of the United States, residing at Worcester, in the county of Worcester and 5 Commonwealth of Massachusetts, have invented a new and useful Improvement in Feeding Mechanism for Gas-Producers, of which the following, together with the accompanying drawings, is a specification.

10 The present invention relates to a feeding mechanism for gas producers, and has particular reference to a mechanism of the above type for mechanically supplying fuel to a producer, by the introduction of successive intermittent charges, the mechanism being adjustable to vary the rate at which 15 the charges are introduced, and also to vary the size of said charges, in accordance with the rate of consumption of fuel within the producer.

20 The mechanism belongs to that type of feeder which provides a movable fuel receptacle adapted, in one position to receive a charge of fuel from a chute, hopper or other 25 source of supply, and subsequently, to deliver such charge into the combustion chamber of the producer. One object of my invention is to provide an arrangement and disposition of parts, whereby the operation 30 of devices of this class is improved, with respect to obtaining the greatest possible freedom of movement for the fuel receptacle, and, at the same time, permitting its movement to take place under conditions 35 which eliminate the necessity for shearing through portions of the charge of fuel in the operation of sealing the producer chamber against the escape of gas.

40 Another object is to obtain the most efficient delivery of fuel from the chute or hopper into the charging receptacle, by the provision of novel means for restraining undue deflection of the fuel past the delivery end of said chute as the charging receptacle moves beneath the same. Another 45 object is to provide efficient means for preventing the collection of tar and dirt upon the surfaces of the receptacle and its seat.

Other and further objects and advantages 50 of the mechanism will be particularly described and pointed out in the following description, reference being had to the accompanying drawings, in which—

Figure 1 is a sectional view of a gas pro-

ducer, equipped with fuel feeding means 55 constructed according to this invention.

Fig. 2 is a cross sectional view through the feeding mechanism in a plane at right angles to the section of Fig. 1.

Fig. 3 is a sectional view of the feeding 60 mechanism in the plane of the line 3—3, Fig. 2.

Fig. 4 is an end view of the feeding mechanism.

Fig. 5 is a detail view of an actuating rod. 65

Fig. 6 is a fragmentary view of the driving mechanism associated with the feeding device.

Like reference characters refer to like 70 parts in the different figures.

Referring to the accompanying drawings, the gas producer shown in Fig. 1 provides a combustion chamber 1 which is inclosed by a stationary cover section 2, the latter being preferably water cooled, and having an 75 opening 3 in its top, for the entrance of fuel. The opening 3 communicates with the interior of a hollow water cooled shell 4 superposed upon the top of the producer, and providing for the support of the fuel feeding mechanism forming the subject matter 80 of this invention.

The said fuel feeding mechanism consists of an open ended casting or cradle 5 providing a concave seat 6, from which opens 85 downwardly a passage 7, communicating, through the shell 4 and opening 3 with the combustion chamber 1. Bolted to each flanged end of the cradle 5 is a plate 8, the said plates 8 providing aligned vertical recesses 9 for the reception of adjustable bearing blocks 10, supported upon set screws 11. Bearing blocks 10, 10 afford journals for trunnions 14, 14 which project from the ends of a cylindrical drum or receptacle 15. 90 The latter is adapted to rotate in the concave seat 6, between the end plates 8, 8. As herein shown, the circumferential extent of the seating surface 6 of the cradle 5 is slightly less than one half the circumference 100 of the drum 15, whereby the latter is free to move away from said seating surface during its rotation, since the cradle does not extend far enough around the drum for the parts ever to bind.

105 In other words, all danger of the drum sticking or binding in the cradle, by expansion or otherwise, is effectually prevented

by thus limiting the seating surface to not more than one half the circumference of the drum, thereby permitting said drum and its trunnions to move not only rotatively, but 5 also away from said seating surface. Movement away from the seating surface is limited by means of adjustable set screws 13, 13 carried by plates 12, 12 which project upwardly from the plates 8, 8. These set 10 screws 13, 13 are adapted to bear lightly against the upper ends of the blocks 10, 10 when the drum is in operation. That is, the set screws 13, 13 are set up loosely when the feeding mechanism is cold; after the 15 producer is started, and the parts have heated up and expanded in the normal operation, these set screws allow the drum to assume a position for free rotative movement in the cradle, while at the same time 20 holding it properly to its work. In the event of undue or unusual heating and expansion of the drum, the set screws 13, 13 may be still further slackened off, as will be readily understood. In other words, 25 these set screws perform by their adjustability, in effect, the same function as a yielding spring or a weight, except that in practice they afford a better means of holding the drum to its work and thus prevent any 30 accumulation of tar or dirt on the contacting surfaces of the drum and cradle.

The removal of any such accumulation of tar or dirt is assisted by the provision of longitudinally finished strips 16, 16, Fig. 2, 35 on the surface of the drum, these strips being the parts of the drum which are in actual contact with the seat 6. The edges of these strips serve to scrape the surface of the cradle, in the rotation of the drum, and 40 these strips are arranged sufficiently close together so as to provide a sealing contact with the portions of the seat 6 which are on opposite sides of the passage 7. Furthermore, by thus limiting the contacting surface 45 between the drum and cradle, the friction between these parts is materially reduced.

A fuel spout 17 leading from the hopper, or other source of fuel supply, has suspended 50 therefrom a trough or chute 18, the longitudinal axis of which is inclined with respect to the perpendicular, with its delivery end disposed adjacent the surface of the drum 15 at one side of the axis thereof. 55 The flow of fuel from the spout 17 through the chute 18 against the wall of the drum 15 is controlled by a sliding gate 19, which is adjustable up and down to vary the distance of its lower end from the bottom of the 60 chute 18, and thereby to vary the effective fuel opening afforded by the delivery end of said chute. The adjustment of the gate 19 is determined by the position of a transverse rod 20, removably carried within an 65 upturned portion of the gate, there being a

series of vertically spaced holes 21 in the side walls of said chute, to receive the ends of said rod. In this manner the area of fuel resting by gravity against the surface of the drum, and supporting the column of fuel 70 contained within the inclined chute 18 and the spout 17, is varied.

The drum 15 has a longitudinal opening 22 in its wall; the circumferential extent of this opening is approximately one-sixth the 75 circumference of the drum. It will be seen that this opening must be of less width than the effective sealing surfaces of the seat 6 of the cradle on opposite sides of the passage 7, since, in the rotation of the drum, in 80 the direction of the arrow, Fig. 2, communication between its interior, and the interior of the producer, must be completely closed before the leading edge of the opening arrives at the delivery end of the chute 18. 85 By reason of the inclination of the chute 18, and in consequence of the disposition of its delivery end wholly at one side of a vertical line passing through the axis of the drum, the natural flow of fuel through the necessarily restricted opening 22, when the latter is in the position shown in Fig. 2, can never completely fill the drum, since the angle of repose assumed by the fuel does not include 90 the upper portion of the drum, on the opposite side of its axis from the chute 18. The mass of fuel thus isolated within the drum being therefore free and mobile, there is no undue resistance to the shearing action of the rear edge 23 of the opening 22, as 100 would exist if the drum were completely filled at each revolution. In other words, the sealing edge afforded by the drum to prevent the escape of gases from the combustion chamber of the producer, is located 105 above the level of the coal which has been isolated within the drum.

The chute 18 is entirely open on its upper side; however, means must be provided for preventing the fuel from being carried out 110 of the chute by the rotation of the drum, and such means conveniently take the form of a flexible guard which, while holding back the greater portion of the fuel, will allow the large lumps caught in the opening 22 to pass forward without damage to the feeder, or without raising the guard throughout its entire length; as shown in Figs. 2 and 3, stiff wire brushes 24 having their ends in scraping contact against the 115 periphery of the drum, are employed for this purpose. Said brushes are carried upon a bar 25 supported by the plates 12, 12 at the ends of the cradle.

It is necessary to provide, in this connection, devices for removing tar and coal dust from the surface of the drum and particularly the recesses between the finished strips 16; such devices are embodied in wire brushes 26 disposed in advance of the fuel 125 130

retaining brushes 24. If desired, a scraper 27 pivoted on a rod 28 extending between the plates 12, 12 may be employed, with its free end resting upon the surface of the drum, for the purpose of removing coal dust, and preventing the passage of small particles of coal which may have passed the brushes 24 and 26, from being carried onto the supporting and sealing surfaces afforded by the cradle 5. For further preventing the access of foreign matter to the seat 6 of the cradle, a rigid scraper 29, supported by the cradle, is provided, the same being adjustable toward and from the surface of the drum to scrape the tar therefrom.

As a means for imparting rotation to the drum, one of the trunnions 14 carries a flanged disk 30, providing inner peripheral surfaces for engagement by a pair of friction shoes 31, one only being shown, and an outer peripheral surface for engagement by a single friction shoe 32, Fig. 6. Said shoes 31 and 32 are pivotally mounted on a bifurcated link 33 which extends inwardly from the lower end of a toggle lever 34, being pivotally attached thereto at 35. The toggle lever 34 is carried on the free end of an arm 36 of a bell crank, journaled on said trunnion 14, the other arm 37 of said bell crank having a pivotal connection with a two part horizontal connecting rod 38, pivotally attached at its other end to a rocking arm 39. The arm 39 is oscillated through the medium of an eccentric 40 and is provided with a series of holes 41, whereby the pivotal connection thereto of the rod 38 may be changed, to vary the stroke of said rod. The reciprocation of the rod 38 effects a step-by-step rotation of the drum through the action of the friction shoes 31 and 32, the movement of the rod 38, to the left, Fig. 1, causing said shoes to bind upon the flanges of the disk 30, thereby carrying the drum in the direction of the arrow, Fig. 2, while the movement of the rod 38 to the right carries the shoes 31 and 32 out of frictional contact with the rims of the disk, with the result that the drum remains stationary during such movement. The connecting rod 38 is constructed in such a manner that an undue resistance to the rotation of the drum will enable said rod to become ineffective in rotating the drum until such resistance is removed. To this end the rod is made in telescopic sections 42 and 43, one of which, 42, has pivoted thereto a weighted latch 44 providing a shouldered cam surface 45 for engagement by a transversely projecting pin 46 carried by the other section 43. Under normal conditions the thrust of the section 42 to the left of Figs. 1 and 4 is sustained by the pin 46, causing the shoes 31 and 32 to operate in moving the drum in the manner above described; if, however, the resistance to such movement exceeds a

predetermined limit, the inclined surface 45 rides upwardly on the pin, lifting the latch 44 and moving the part 42 independently of the part 43, whereupon no motion in an operative direction is imparted to the bell 70 crank 35—36.

The intermittent rotation of the drum 15, in the manner above described, provides for the isolation of measured charges of fuel therein, and the subsequent introduction of 75 the same into the combustion chamber of the producer. Each charge is always less than the total capacity of the drum; the size of the charges may be varied by adjustment of the gate 19, and the rate at which 80 successive charges are introduced may be varied by adjustment of the stroke of rod 38, through its connection with arm 39.

Obviously, the drum 15, instead of rotating always in one direction, as shown, may 85 have imparted thereto an oscillating movement, to carry its opening 22 alternately back and forth, into registry with the end of the chute 18 and the passage 7, respectively. 90

It will be apparent that the adaptation of a fuel feeder of the above type to a gas producer, requiring at all times the maintenance of a seal against the escape of gas, involves a construction in which the rear 95 edge 23 of opening 22 moves into sealing contact with the seat 6 of cradle 5 before the forward edge of said opening arrives at the passage 7, in order to seal the producer chamber against the escape of gas. It is 100 proper to say, therefore, that the arrival of the edge 23 at a radial plane where it makes sealing contact with the seat 6 of the cradle fixes and determines a sealing edge for the feeder, in the operation of discharging the 105 contents of the receptacle into the producer chamber. In the same way, the arrival of said edge 23 at a radial plane where it makes sealing contact with the seat 6, on the opposite side of the passage 7, effectually 110 prevents the escape of gas from the producer chamber, in the operation of moving the receptacle into position to receive a charge, since said edge 23 must arrive upon the seat 6 before the forward edge of opening 22 passes off the seat. It follows, therefore, that in confining the effective sealing surface of the cradle to not more than one half of the circumference of the drum, for the purposes heretofore set forth, the maximum width of the opening 22 is limited to somewhat less than one-sixth of the circumference of the drum, as clearly shown in Fig. 2. 115

The sealing edge, in the operation of discharging the receptacle, being located below the horizontal plane containing the axis of rotation of the receptacle, it is clear that the charging of the drum to its full capacity would result in a spilling of fuel 120 125 130

through the opening 22 as the latter approaches the vicinity of the scraper 29. Moreover, under the conditions above described, the rear edge 23 of said opening 5 would be called upon to shear through the fuel, as the said edge approached its sealing position, causing an undue resistance to the movement of the drum and, therefore, precluding the successful operation of the feeding mechanism. The present invention resides, primarily, in the combination and arrangement of instrumentalities by which the above noted disadvantages are eliminated, while still retaining the advantages 10 incident to the provision of a cradle which embraces not more than one half the circumference of the drum. Due to the fact that the measured charge of fuel which enters the drum from the chute or hopper is 15 always definitely limited to a volume less than the total capacity of the drum, the fuel constituting said charge always seeks a level in the drum below the plane of the sealing edge, by the time that the opening 20 22 has been moved into the vicinity of said sealing edge. That is to say, that portion of the fuel in the drum which lies nearest said sealing edge is always lower than said sealing edge, on account of the angle of re- 25 pose which the fuel assumes in response to rotation of said drum. As a consequence, no fuel spills through the said opening as the latter draws near to and assumes a horizontal position, nor is there any necessity for 30 a shearing action of the rear edge 23 of said opening, as said edge moves into sealing contact with the surface of the cradle.

The invention further resides in the provision of the yielding wall afforded by the 40 wire brushes 24, as heretofore explained, and in the provision of the several combinations of instrumentalities fully set forth in the following claims.

It is to be understood that the term "sealing edge," as hereinafter used in the annexed 45 claims, has reference to the hereinbefore described location fixed by the arrival of the edge 23 in sealing contact with the seat 6 of cradle 5 in the operation of discharging the contents of the drum into the producer chamber.

The provision on the surface of the drum of the longitudinal finished strips 16 insures the freeing of the seating surface of the 55 cradle from deposits of tar or coal dust which might be carried thereon in the continued operation of the feeder. The scraping devices, heretofore described serve, in turn, to remove such foreign matter from 60 the surface of the drum.

The provision of a substantially gas tight seal, by the coöperation of the drum with the seating surface of the cradle, as herein- 65 after specified in the annexed claims, has reference merely to such a seal as would pre-

clude the excessive escape of gas from the combustion chamber of the producer, and is not to be construed as limiting said claims to a construction providing a drum and cradle fitted with such exactitude that no 70 leakage of gas could take place.

I claim:

1. In a fuel feeding mechanism, a rotatable ported charging member having its axis free to shift radially, and a supporting means 75 for said member providing a concave seat whose effective surface embraces not more than one half the circumference of said member, whereby said radial shifting movement of the axis of said member is permitted. 80

2. In a fuel feeding mechanism for gas producers, a rotatable charging member having an opening, a supporting means for said member providing a concave seat whose effective surface embraces not more than one half the circumference of said member, said seat providing a passage to the producer chamber for registration with said opening, a sealing surface on each side of said passage, the width of each sealing surface being 85 greater than the width of said opening, and means for removing tar and dirt from the surface of said rotatable member. 90

3. In a fuel feeding mechanism for gas producers, a rotatable ported charging member having its axis free to shift radially, and a supporting means for said member providing a concave seat whose effective surface embraces not more than one half the circumference of said member, whereby said radial shifting movement of the axis of said member is permitted, said seat providing a passage to the producer chamber for registration with the port of said member, and a sealing surface on each side of said passage, the width of each sealing surface being greater than the width of said port. 100

4. In a fuel feeding mechanism for gas producers, a rotatable charging member having an opening, a supporting means for said member providing a concave seat whose effective surface embraces not more than one half the circumference of said member, said seat providing a passage to the producer chamber for registration with said opening, 110 said seat and said member coöoperating to form a substantially gas tight seal against the escape of gas from the producer chamber in every position of said member, and means for limiting the charge received by 115 said member to a volume less than the capacity of said member. 120

5. In a fuel feeding mechanism for gas producers, a rotatable charging member having an opening, a supporting means for said member providing a concave seat having a passage to the producer chamber for registration with said opening, and means for segregating a charge of fuel in said member, of such a size as to prevent the 125 130

- lodgment of fuel between the edge of said seat and the rear edge of said opening, in the rotation of said member.
6. In a fuel feeding mechanism for gas producers, a rotatable charging member having an opening, a supporting means for said member providing a concave seat having a passage to the producer chamber for registration with said opening, and means for segregating a charge of fuel in said member, of such a size as to prevent the lodgment of fuel between the edge of said seat and the rear edge of said opening, in the rotation of said member, the member and said seat coöperating to form a substantially gas tight seal against the escape of gas from the producer chamber in every position of said member. 75
7. In a fuel feeding mechanism for gas producers, a rotatable charging member, a seat for said member embracing less than the full circumference thereof, and means for removing tar and dirt from the surface of said charging member. 80
8. In a fuel feeding mechanism for gas producers, a rotatable charging member, a seat for said member embracing less than the full circumference thereof, means for removing tar and dirt from the surface of said charging member, and means carried by said charging member for removing tar and dirt from the surface of said seat. 85
9. In a fuel feeding mechanism for gas producers, a rotatable charging member, a fuel feeding spout mounted in operative relation thereto, and a guard extending across and forming one side of said spout, said guard comprising a plurality of independently yieldable sections. 90
10. In a fuel feeding mechanism for gas producers, a member providing a concave seat having a passage leading therefrom to the producer chamber, a cylindrical fuel charging member journaled in said seat and having an opening for coöperation with said passage, the effective surface of said seat embracing not more than one half the circumference of said member, and means for limiting the charge received by said member, whereby to prevent the discharge of fuel through said opening prior to its registration with said passage. 100
11. In a fuel feeding mechanism for gas producers, a chute providing for the gravity flow of fuel, a rotatable hollow member having an opening for registration periodically with the delivery end of said chute, a portion of said member being disposed above the slope assumed by the fuel in reaching its angle of repose as it passes by gravity through said opening and into said hollow member, whereby the filling of said member to its full capacity is prevented, and means for varying the effective area of the delivery end of said chute. 115
12. In a fuel feeding mechanism for gas producers, a chute providing for the gravity flow of fuel, a rotatable hollow member having an opening for periodic registration with the delivery end of said chute, and a yielding wall comprising independent sections extending across said chute and disposed opposite the bottom of said chute, against which the fuel is carried by the rotation of said member. 75
13. In a fuel feeding mechanism for gas producers, a chute providing for the gravity flow of fuel, a rotatable hollow member having an opening for periodic registration with the delivery end of said chute, and means, yieldable in sections across the width of said chute, for retarding the movement of fuel out of said chute as urged forward by the rotation of said member. 80
14. In a fuel feeding mechanism for gas producers, a chute open on its upper side and providing for the gravity flow of fuel, a rotatable hollow member having an opening for periodic registration with the delivery end of said chute, and yielding means comprising independent sections, disposed across the upper side of said chute, for retarding the movement of fuel out of said chute. 85
15. In a fuel feeding mechanism for gas producers, the combination with a rotatable charging member, of a seat therefor providing a passage to the producer chamber and coöperating therewith to form a substantially gas tight seal against the escape of gas from the producer chamber in every position of said member, and means carried by said member for removing tar and dirt from the surface of said seat by the rotation of said member. 95
16. In a fuel feeding mechanism for gas producers, a member providing a concave seat having a passage leading therefrom to the producer chamber, a cylindrical fuel charging member journaled in said seat for coöperation with said passage, the effective circumferential extent of said seat being not more than one half the circumference of said member, and means for scraping the surface of said member in advance of its passage into contact with said seat. 110
17. In a fuel feeding mechanism for gas producers, a rotatable member adapted in one position to receive a charge of fuel, and in another position to discharge the same into the producer, a supporting means in which said member is journaled, said supporting means being effective with respect to not more than one half the circumference of said member, and coöperating therewith to form a substantially gas tight seal in all positions of said member, and means for varying the pressure of said member upon said supporting means. 125
18. In a fuel feeding mechanism for gas producers, a rotatable member adapted in one position to receive a charge of fuel, and in another position to discharge the same into the producer, a supporting means in which said member is journaled, said supporting means being effective with respect to not more than one half the circumference of said member, and coöperating therewith to form a substantially gas tight seal in all positions of said member, and means for varying the pressure of said member upon said supporting means. 130

- producers, a rotatable member adapted in one position to receive a charge of fuel, and in another position to discharge the same into the producer, a supporting means in which said member is journaled, said supporting means being effective with respect to not more than one half the circumference of said member, and coöperating therewith to provide a sealing edge, as said member approaches discharging position, and means for maintaining the level of the fuel charge in said member below said sealing edge, as said member approaches its discharging position.
- 15 19. In a fuel feeding mechanism for gas producers, a rotatable ported charging member having its axis free to shift radially, a supporting means for said member providing a concave seat whose effective surface 20 embraces not more than one half the circumference of said member, whereby said radial shifting movement of the axis of said member is permitted, said seat providing a passage to the producer chamber for registration with the port of said member, and said seat and said member coöperating to form a substantially gas tight seal against the escape of gas from the producer chamber in every position of said member.
- 25 20. In a fuel feeding mechanism for gas producer, a rotatable hollow fuel charging member having an opening, means coöperating with said member to provide a sealing edge below the axis of rotation of said member, and a fuel chute having its delivery end disposed at one side of said axis of rotation, in position for periodic registration with said opening, whereby the level of fuel in said member is maintained below said 30 sealing edge.
- 35 21. In a fuel feeding mechanism for gas producers, the combination with a rotatable fuel charging member having an opening, of a seating means effective with respect to not 40 more than one half the circumference of said member, said seating means providing a passage for coöperation with said opening to receive therefrom the charge of fuel carried by said member, and means for preventing 45 the charging of said member to its full capacity, whereby the movement of said opening onto said seating means is unobstructed.
- 50 22. In a fuel feeding mechanism for gas producers, the combination with a rotatable charging member, of a seat therefor providing a passage to the producer chamber and coöperating therewith to form a substantially gas tight seal against the escape of gas from the producer chamber in every position 55 of said member, said member having spaced

longitudinal ribs on its periphery in contact with said seat.

23. In a feeding mechanism for gas producers, a rotatable hollow member adapted in one position to receive a charge of fuel, and in another position to discharge the same into the producer chamber, means for limiting the volume of each charge of fuel received by said member, and means for providing a sealing edge against the escape of gas from the producer chamber as said member approaches its discharging position, said sealing edge being located above the level assumed by the charge of fuel within said hollow member.

75 24. In a feeding mechanism for gas producers, a rotatable hollow charging member having an opening for the discharge of its contents into the producer chamber, means for limiting the volume of each charge of fuel received by said member, and means for providing a sealing edge against the escape of gas from said chamber as said member approaches its discharging position, said sealing edge being located above the level assumed by the charge of fuel within said member, when the rear edge of said opening approaches said sealing edge.

80 25. In a feeding mechanism for gas producers, a rotatable hollow charging member having an opening for the discharge of its contents into the producer chamber, means for limiting the volume of each charge of fuel received by said member, and means for providing a sealing edge against the escape of gas from said chamber as said member approaches its discharging position, said sealing edge being above the adjacent portion of the fuel charge within said member when the rear edge of said opening approaches said sealing edge.

85 26. In a fuel feeding mechanism for gas producers, a hollow rotatable charging member, supporting means for the trunnions of said member adapted to permit limited radial shifting of the axis thereof, and a seat for said member whose effective surface embraces not more than one half of the circumference of said member, whereby said shifting of the axis is permitted, said seat coöperating with said member to form a substantially gas tight seal against the escape of gas from the producer chamber in all positions of said member.

100 Dated this 24th day of June, 1915.
